FREDERIC VALPEY SHOTWELL, OF DETROIT, MICHIGAN, ASSIGNOR OF ONE-HALF TO GRIFFITH-HOPE COMPANY, OF WEST ALLIS, WISCONSIN, A CORPORATION OF WISCONSIN, AND ONE-HALF TO FRED M. SHOTWELL, OF DETROIT, MICHIGAN

CARD-INDEX FILE

Application filed November 21, 1928. Serial No. 320,868.

The invention relates to card index files.

An object of the invention is to provide a simple and inexpensive card index file, more particularly adapted for the filing of recipes for use in a kitchen, but also capable of other applications.

Another object of the invention is to provide a card index file including a container having a pencil-receiving rest formed thereon at its front wall.

A further object is to construct the container from sheet metal in a simple but effective manner and to form the pencil rest by means of an offset in its front wall.

15 A further object is to provide a card index file including a pivoted inclined cover, so constructed as to form a rest receiving a selected one of the recipe cards.

20 A further object is to so construct the container that it may rest either on a horizontal surface or on a wall, and to so arrange the cover that it will be retained in open position when the container is mounted against a wall.

25 A further object is to provide a set of index cards for the file arranged in groups, the several cards in each group having laterally offset index tabs and the cards in each successive group being higher than those in the preceding group to secure visibility of the tabs thereon.

30 A further object is to construct the index cards in the form of folders which can be selectively withdrawn to afford convenient access to the group of cards contained therein.

A further object of the invention is to perfect details of construction generally.

The invention further consists in the several features hereinafter set forth and more particularly defined by the annexed claims.

In the accompanying drawings,

Fig. 1 is a transverse sectional elevation of a card index file embodying the invention, as it appears when mounted on a wall and with its cover in open position some of the index folders being omitted;

Fig. 2 is a longitudinal sectional elevation of the card index file taken near the front wall thereof and showing the cover in its open position;

Fig. 3 is an end elevation of the card index file with its cover in closed position and forming a rest for a recipe card, and a pencil being supported along the front wall of the file, and

Fig. 4 is a front elevation of the card index file as it appears when supporting a pencil and a selected exposed recipe card.

In these drawings, the numeral 10 designates a rectangular container of sheet-metal construction in which the front, bottom and back walls are formed of a single piece of sheet-metal 11 joined, as by welding, to marginally flanged sheet metal panels 12 forming opposite end walls, the flanges 12' of the end panels being disposed within the sheet-metal member 11. The bottom of the container is provided with embossments 13 upon which the container may rest on a table surface or other horizontal surface, and the back wall is provided with keyhole-shaped slots 14 for receiving there-through screws 15 by means of which the container may be mounted against a supporting wall.

The front wall of the sheet-metal member 11 is bent at an intermediate portion to form a longitudinally-extending rearwardly-inclined shelf or ledge 16 adapted to support thereon a pencil 17 or other writing instrument. The upper edge of the rear wall of the member 11 is somewhat higher than the upper edge of the front wall, and the upper edge of each of the end wall panels 12 is inclined to extend between the upper edges of the front and back walls. The upper portion of the rear wall is curved forwardly to fit about the correspondingly rounded upper edges of the end wall panels 12, and the upper edge of the rear wall is rolled to form a hinge 18 with similarly rolled portions of a sheet-metal cover 19. The cover 19 is provided with depending flanges 20 at its ends, which enclose the upper edge portions of the end walls 12 when the cover is in closed position, as seen in Fig. 3. At its forward edge the cover 19 is provided with an upwardly-projecting rolled bead 21, which not only serves as a handhold for lifting the cover, but also forms a ledge by means of which a

card can be rested on the upper face of the inclined cover.

The container 10 receives therein a group of folders 22 each holding therein a group of recipe cards 23 and each folder having an index tab 24 formed thereon at the upper edge of its rear leaf. For clarity, some of the folders are omitted from Fig. 1. The folders 22 are arranged in several groups, 5 the folders in any one group being of the same height and the folders in the next posterior group being of greater height. The index tabs on the folders in any one group are offset laterally to obtain visibility of each tab, 10 and the index tabs in the succeeding posterior group are also offset in the same manner but are arranged at a higher elevation to be visible above the tabs of the preceding group. In this manner, every index tab is readily 15 visible at a glance without requiring manipulation of the folders. It will be noted that the front leaves of the several folders are all of the same height, as are also the cards 23, and that the rear leaves of the folders are of 20 variable height.

Each folder 22 contains all recipe cards describing foods of a general class, such as "beverages", "breads", and "cake", and a selected one of the folders is lifted to the position 25 seen in Fig. 1, when the cover 19 is open, to permit the withdrawal therefrom of any selected recipe card. The folder is then dropped to its normal position within the container and the cover is dropped to the 30 closed position, as seen in Figs. 3 and 4. The selected recipe card is then placed in inclined position on the cover, as seen in Figs. 3 and 4, to be conveniently visible for frequent 35 reference. In this position, the card is not likely to become accidentally soiled or damaged.

The cover, when moved to its open position, as seen in Fig. 1, remains in such position even when the container is mounted 40 against a supporting wall, since the center of gravity of the open cover is spaced rearwardly from the vertical plane of the hinge 18.

What I claim as new and desire to secure 45 by Letters Patent is:

1. A card index file comprising a card-receiving container including a sheet-metal front wall having an offset formed therealong at an intermediate portion to present a 50 pencil-receiving ledge.

2. In a card index file, the combination of a card-receiving container, and an inclined sheet-metal cover for said container sloping forwardly and downwardly and having an 55 upwardly projecting flanged portion along its forward free edge to form a card-receiving stop, whereby a card forming part of said file may be supported on said inclined cover when the latter is in closed position.

3. In a card index file, the combination of

a card-receiving container, and an inclined sheet-metal cover for said container sloping forwardly and downwardly and having an upwardly-projecting handhold-forming bead along its forward free edge to provide a card-receiving stop channel, whereby a card forming part of said file may be supported on said inclined cover when the latter is in closed position.

4. In a card index file, the combination of a plurality of upwardly opening card-receiving index folders arranged in a plurality of successive groups, the folders in any one group being of the same height and provided with index tabs arranged in offset relation, 75 and the folders in the succeeding groups being of greater height at their rear leaves and having their index tabs arranged at a different elevation to obtain visibility of all of said index tabs without manipulation of said folders, and a plurality of cards received in each folder, the cards in all the folders being of the same height and having their upper edges below the level of the lowermost tabs.

5. A card index file comprising a rectangular sheet-metal card-receiving container having front, rear and end walls, said end walls having their upper edges sloping downwardly from rear to front, and a sheet-metal cover hingedly connected to the upper edge 95 portions of said rear wall and sloping forwardly and downwardly to the upper edge portions of said front wall, said cover having depending flanges at its side edges adapted to overlie the side walls of said container and the forward portions of said cover being rolled to form an upwardly projecting bead 100 constituting a stop ledge for a card resting on the sloping cover.

6. In a card index file, a plurality of upwardly opening card-receiving index folders arranged in a plurality of successive groups, the folders in any one group being of the same height and provided with index tabs on their rear leaves arranged in offset relation, and the folders in the succeeding posterior groups being of greater height at their rear leaves and having their index tabs arranged at a higher elevation to obtain visibility of all of said index tabs without manipulation of said folders, the front leaves of all of said folders being of the same height and having their upper edges below the level of the lowermost tabs.

In testimony whereof, I affix my signature.

FREDERIC VALPEY SHOTWELL.
